FURNITURE BASE

George Kasparian, Los Angeles, Calif., assignor to Kasparians, Inc., Los Angeles, Calif., a corporation of California

Filed Mar. 29, 1962, Ser. No. 69,476

Term of patent 14 years

(Cl. D15—1)

for a furniture base;

I claim:

The ornamental design for a furniture base, substantially as shown.
